UNITED STATES PATENT OFFICE.

CHARLES W. TREMPER, OF NEW HAVEN, CONNECTICUT, ASSIGNOR, BY MESNE ASSIGNMENTS, TO THE TREMPER-SHIELDS COMPANY, OF NEW HAVEN, CONNECTICUT, A CORPORATION OF CONNECTICUT.

SUCTION SHEET-PICK-UP MECHANISM.

Application filed November 6, 1926. Serial No. 146,689.

My invention relates to an improved sheet-pick-up mechanism, the object being to produce a simple, compact, convenient and reliable mechanism of the "suction" type, constructed with particular reference to reducing the lateral displacement of the sheet being picked up to the minimum.

A further object of my invention is to provide a mechanism which, in addition to picking up the sheet with the minimum of lateral displacement, will forward it.

With these ends in view, my invention consists in a sheet-pick-up mechanism having a plurality of suction pick-up members and yielding means for depressing such members into engagement with the sheet and for thereafter counteracting the lifting action of the suction, whereby the lifting and canting of the sheet by suction is prevented.

My invention further consists in a sheet-pick-up mechanism having a plurality of suction pick-up members, yielding means for depressing such members into engagement with the sheet and for thereafter counteracting the lifting action of the suction, whereby the lifting and canting of the sheet by suction is prevented, and means for bodily moving the said pick-up members in a plane at a right angle to their lifting action.

My invention further consists in a mechanism characterized as above and having certain other details of construction and combinations of parts as will be hereinafter described and particularly pointed out in the claims.

In the accompanying drawings:

Fig. 1 is a broken view in rear elevation of my improved sheet-pick-up mechanism;

Fig. 2 is a view thereof in side elevation, with the parts in the positions due to them when the suction-pick-ups are about to descend into engagement with the topmost sheet of paper in the pile;

Fig. 3 is a corresponding view with the parts in the positions due to them after the suction-pick-up has engaged with the topmost sheet of paper in the pile and before the said sheet has been lifted;

Fig. 4 is a corresponding view showing the parts in the positions due to them after the completion of the lifting-and-forwarding movements of the mechanism;

Fig. 5 is a vertical sectional view on an enlarged scale on the line 5—5 of Fig. 3; and

Fig. 6 is a horizontal sectional view on the line 6—6 of Fig. 3.

In the machine chosen for the illustration of my invention, I employ two complementary pick-up mechanisms or units mounted over a pile of paper in spaced relation to the forward edges of the sheets composing the pile. Inasmuch as these mechanisms or units correspond to each other, a description of one of them will suffice for both. Each of the said mechanisms or units comprises a conical, rubber suction-cup 10 carried by the lower end of a hollow piston 11 through the medium of a head 12 sleeved over and secured to the same and receiving a concentric screw 13 which seats the upper edge of the cup in a counterbore 14 in the said head, the said screw being provided with an axial passage 15 leading into the hollow piston 11 aforesaid. The said piston reciprocates vertically in a hollow cylinder 16 connected at its upper end with a flexible tube 17 connected to any suitable vacuum pump, not shown. The cylinder itself has its lower portion sweated into a boss 18 offsetting from a horizontally-movable forwarding carriage 19 provided with two rollers 20 and 21 working in a guide-slot 22 in a mounting-plate 23 upon which the mechanism or unit now being described is installed, the roller 20 being mounted upon a stud 20^a fixed in the said carriage 19. The said mounting-plate and the mounting-plate of the complementary mechanism or unit are supported at their forward ends by a horizontal tie-rod 24 and at their upper rear ends by a rock-shaft 25, 90

the said tie-rod and rock-shaft being arranged transversely to the machine.

The cylinder 16 aforesaid is formed in its outer face with a vertical slot 26 (Fig. 5), while the boss 18 is formed with a corresponding slot 27 for the clearance of a horizontal stud 28 projecting outwardly from the piston 11 and provided at its outer end with a roller 29 co-acting with a yielding depressing-finger 30 extending over it and engaging with its upper face and also co-acting with a lifting-finger 31 extending under it and co-acting with its under-face. The depressing-finger 30 aforesaid rocks

upon the projecting outer end of a stud 32 rigidly mounted in the carriage 19 and at its opposite end carrying the guide-roller 21 aforesaid.

5 For the purpose of yieldingly depressing the finger 30, I employ a helical torsion spring 33 encircling the projecting end of the stud 32 and having its inner end inserted into the outer face of the finger and its outer end inserted into an adjusting-disk 34 formed in its outer face with two diametric grooves 35 arranged at a right angle to each other and receiving a locking-pin 36, whereby, by pushing the adjusting-disk inward 10 against the tension of the said spring, the disk may be rotated in one direction or the other for adjusting the tension of the spring, after which the disk has one or the other of its grooves 35 engaged with the locking-pin 36.

15 The lifting-finger 31 aforesaid forms a part of a bell-crank-lever 37 hung upon a stud 38 in the rear end of the carriage 19 and provided with a depending arm 39 having its lower end forked to receive a stud 40 in the lower end of an operating-arm 41 secured to the rock-shaft 25 by a set-screw 42, and partaking of the rocking movement thereof. The said bell-crank-lever mounts a 20 roller 43 co-acting with an arcuate locking-slot 44 formed in the rear end of the mounting-plate 23 and intersecting the rear end of the guide-slot 22 aforesaid. The said roller 43 turns on a stud 45 projecting outwardly 25 from a boss 46 formed upon the bell-crank-lever. For the clearance of the said boss, as the lever 37 swings upon its stud 38, an arcuate clearance-slot 47 is formed in the rear end of the carriage 19.

30 The operating-arms 41 of the two separate mechanisms or units now being described are mounted in fixed relation upon the rock-shaft 25 and properly spaced apart thereupon, as shown in Fig. 1. For the rocking 35 of this shaft, it is furnished with an up-standing arm 48 mounting a roller 49 turning on a stud 50 and co-acting with an operating-cam 51 on a horizontal cam-shaft 52. The roller 49 is maintained in contact with 40 the periphery of the cam 51 by means of a helical spring 53 attached at its rear end to the upper end of the arm 48 and at its forward end to a tie-rod 54.

45 In the operation of my improved mechanism, any suitable vacuum pump draws a current of air upward through the suction-cup 10, passage 15, hollow piston 11, hollow cylinder 16, and flexible tube 17 of the respective suction pick-up mechanisms or units. Either vacuum caused by the said pump, or the springs 33, or both, will be adjusted so as to effect a substantial counter-balance between the lifting power of the suction-cups and the depressing power of the 50 said yielding depressing fingers.

It is to be further understood that in the varying conditions of use, the top of the pile of sheets will sometimes be level and sometimes not, the last-named condition being beyond the control of the user of the machine. In describing the operation of my improved sheet-pick-up mechanism, it will be assumed that the top of the pile of sheets is not level, since my mechanism is constructed with particular reference to taking care of such a contingency, which is of frequent occurrence.

55 Assuming that the mechanism is running, a cycle in the operation of my improved mechanism will be as follows:

Starting with the positions of the parts shown in Fig. 2, in the turning of the cam-shaft 52 the roller 49 will pass the contiguous high point of the cam, thus permitting the spring 53 to rock the shaft 25 and swing the operating-arms 41 of the two units from front to rear, whereby the bell-crank-lever 37 of each of the units will be swung downward, with the effect of swinging the two lifting-fingers 31 downward to 60 the limit of their depressed positions and of moving the rollers 43 downward into the locking-slots 44. The movement of the lifting-fingers 31 to the limit of their downward positions permits the springs 33 to 65 act through the depressing-fingers 30 to move the pistons 11 downward, whereby the suction-cups 10, carried by them, successively engage the topmost sheet of the pile. At the instant the respective cups, acting independently, make contact with the upper face of the upper sheet of the pile, the cups will be sealed, with the result that the vacuum created within them and there pistons will immediately counteract the downward thrust 70 of the depressing-fingers 30, whereby the downward movement of the pistons and cups will be instantly checked, in which position the cups will remain stationary. The parts are now in the positions in which they are 75 shown in Fig. 3. The piston and cup of each mechanism, whatever their relative vertical positions within the range of their vertical movement, will temporarily remain at rest in these positions, there being no recession 80 or upward movement of either cup, due to suction. The continued turning of the cam 51 swings the arms 41 forward and exerts an effort to move the carriages 19 of the two mechanisms or units forward, but this movement is temporarily resisted by the engagement of their rollers 43 with the forward walls of the locking-slots 44, with the effect of rocking the bell-crank-levers 37 and raising the lifting-fingers 31, which will successively engage with the rollers 29 carried by the pistons of the two mechanisms, the interval between the lifting-action of the 85 said fingers for leveling the sheet being dependent upon the difference in the level of 90 125

the portions of the sheet engaged by the respective suction pick-up cups. From the moment both fingers are engaged with their respective rollers, they will act synchronously to bodily lift the leveled sheet to the limit of its upward movement. The continued movement of the two bell-crank-levers brings their rollers 43 into alignment with the rear ends of the guide-slots 22 in the two mounting-plates 23. When this takes place, the carriages of the two mechanisms will be simultaneously unlocked and free to be moved horizontally forward at a right angle to the lifting action of the cups by the continued forward swinging movement of the arms 41, with the effect of forwarding the outer edge of the topmost sheet upon the conveyor-tapes 55 of any approved feed mechanism, herein shown as comprising a tape-roll 56, a take-up roll 57, and a drop-roll 58. The parts are now in the positions shown in Fig. 4.

As the two carriages reach the limit of their forward movement, the suction is temporarily shut off for the release of the paper by the suction-cups 10. While the sheet is being removed from the pile by the said conveyor-tapes, the carriages are being moved rearward to the limit of their rearward motion by the spring 53. Then, as soon as the rollers 49 are brought into registration with the upper ends of the locking-slots 54, as shown in Fig. 2, the spring 53, acting through the arms 41, swings the bell-crank-levers downward, so as to re-enter the said rollers into the slots 54, whereby the lifting-fingers 31 swing downward to permit the depressing-fingers 30 to move the pistons and hence the suction-cups down onto the next sheet, which has now become the top sheet. The cycle above described is now repeated, and so on.

It will be seen from the foregoing description that my improved mechanism is peculiarly adapted to feeding sheets of paper from a pile which does not present a true level surface to the concurrent action of a plurality of suction-cups, since it provides for compensating for irregularities of level by permitting the suction-cups to descend unequally to the extent required by the inequality of the level of the top sheet. The instant one pick-up cup is engaged with the sheet, that instant its downward movement is checked to remain stationary for an interval sufficient to permit the complementary cup to be correspondingly engaged and checked and held stationary. This feature of lifting the sheet entirely independently of the suction means employed for gripping it, and so leveling it, prior to bodily lifting and forwarding it, reduces the displacement and canting of the sheet to the minimum.

I claim:

1. A sheet-pick-up mechanism, having a

plurality of suction pick-up members, and yielding means for depressing such members into engagement with the sheet and for thereafter counteracting the lifting action of the suction, whereby the lifting and canting of the sheet by suction is prevented. 70

2. A sheet-pick-up mechanism, having a plurality of suction pick-up members, and adjustable yielding means for depressing such members into engagement with the sheet and for thereafter counteracting the lifting action of the suction, whereby the lifting and canting of the sheet by suction is prevented. 75

3. A sheet-pick-up mechanism, having a plurality of suction pick-up members, yielding means for depressing such members into engagement with the sheet and for thereafter counteracting the lifting action of the suction, whereby the lifting and canting of the sheet by suction is prevented, and means for bodily moving the said pick-up members in a plane at a right angle to their lifting action. 80

4. A sheet-pick-up mechanism, having a plurality of suction pick-up members, yielding means for depressing such members into engagement with the sheet and for thereafter counteracting the lifting action of the suction, whereby the lifting and canting of the sheet by suction is prevented, and means for first leveling and then synchronously lifting the said pick-up members. 85

5. A sheet-pick-up mechanism, having a plurality of suction pick-up members, yielding means for depressing such members into engagement with the sheet and for thereafter counteracting the lifting action of the suction, whereby the lifting and canting of the sheet by suction is prevented, means for first leveling and then synchronously lifting the said pick-up members, and means for bodily moving the pick-up members in a plane at a right angle to their lifting action. 100

6. A sheet-pick-up mechanism, having a plurality of suction pick-up members, yielding means for depressing such members into engagement with the sheet and for thereafter counteracting the lifting action of the suction, whereby the lifting and canting of the sheet by suction is prevented, means for first leveling and then synchronously lifting the said pick-up members, and means for bodily moving the said pick-up members and leveling and lifting members in a plane at a right angle to the lifting action of the pick-up members. 11

7. A sheet-pick-up mechanism, having a horizontally-movable carriage, suction pick-up members mounted thereupon, yielding means mounted upon the said carriage for depressing such pick-up members into engagement with the sheet, and for thereafter counteracting the lifting action of the suction, whereby the lifting and canting of the

- sheet by suction is prevented, lifting means mounted on the carriage for first leveling and then lifting the said suction pick-up members, and means for bodily moving the carriage and the parts carried thereby in a plane at a right angle to the action of the said suction pick-up members.
8. A sheet-pick-up mechanism, having a horizontally-movable carriage, a plurality of suction pick-up members mounted thereupon, yielding members mounted upon the said carriage for depressing such pick-up members into engagement with the sheet and for thereafter counteracting the lifting action of the suction, whereby the lifting and canting of the sheet by suction is prevented, lifting means mounted on the said carriage for first leveling and then synchronously lifting the pick-up members, and a member having the two-fold function of operating the said lifting means and then moving the carriage and the parts carried thereby forward in a plane at a right angle to the action of the said pick-up members.
9. A sheet-pick-up mechanism, having a horizontally-movable carriage, a plurality of suction pick-up members mounted thereupon, yielding depressing fingers mounted upon the said carriage for depressing such members into engagement with the sheet and for thereafter counteracting the lifting action of the suction, means mounted upon the carriage for first leveling and then synchronously lifting the said pick-up members, and means for bodily moving the carriage and the parts mounted thereupon in a plane at a right angle to the action of the said pick-up members.
10. A sheet-pick-up mechanism, having a horizontally-movable carriage, a plurality of suction pick-up members mounted thereupon, yielding depressing fingers mounted on the said carriage for depressing such members into engagement with the sheet for thereafter counteracting the lifting action of the suction, lifting-fingers for first leveling and then synchronously lifting the pick-up

members, and means for bodily moving the carriage and the parts carried thereby in a plane at a right angle to the action of the said pick-up members.

11. A sheet-pick-up mechanism, having a mounting-plate, a horizontally-movable carriage installed thereon, a plurality of suction pick-up members mounted in the said carriage, yielding means mounted in the carriage for depressing such pick-up members into engagement with the sheet and for thereafter counteracting the lifting action of the suction, lifting means mounted in the carriage for first leveling and then synchronously lifting the said pick-up members, means for bodily moving the carriage in a horizontal plane, and locking means for locking the carriage against horizontal movement during the lifting action of the lifting-members, and automatically releasing it to forward movement after their lifting action has been completed.

12. A sheet-pick-up mechanism, having a mounting-plate formed with a guide-slot and with a locking-slot leading out of the same, a horizontally-movable carriage mounted upon the said mounting-plate and engaging the said guide-slot, suction pick-up members mounted upon the said carriage, yielding means mounted upon the carriage for depressing such pick-up members into engagement with the sheet and for thereafter counteracting the lifting action of the suction, a lifting member for lifting the said pick-up member, and locking-means mounted upon the said lifting member and co-acting with the said guide and locking-slots in the said mounting-plate for restraining the said carriage against horizontal movement during the lifting action of the lifting-member and automatically releasing it to permit the horizontal movement of the carriage when the lifting-member has completed its lifting action.

In testimony whereof, I have signed this specification.

CHARLES W. TREMPER.
